U.S. Cl. D14—3 E

FIG. 1.

FIG. 2.

FIG. 3.

FIG. 4.

FIG. 5.

FIG. 6.

FIG. 1 is a side elevational view of a hopper semi-trailer showing my new design, the opposite side being substantially similar in appearance;

FIG. 2 is a front elevational view;

FIG. 3 is a rear elevational view;

FIG. 4 is a top plan view;

FIG. 5 is a fragmentary transverse sectional view, to an enlarged scale, the plane of the section being indicated by the line 5-5 in FIG. 4; and,

FIG. 6 is a fragmentary longitudinal sectional view to a greater enlarged scale, the plane of the section being indicated by the line 6-6 in FIG. 4.

The broken lines in FIG. 1 are environmental and form no part of the ornamental design claimed herein.

I claim:

The ornamental design for a hopper semi-trailer, as shown and described.
